UNITED STATES PATENT OFFICE.

HUGH M. BOAL, OF CORRY, PENNSYLVANIA.

CIRCUIT-BREAKER.

1,148,437.

Specification of Letters Patent. Patented July 27, 1915.

Application filed May 15, 1914. Serial No. 838,865.

To all whom it may concern:

Be it known that I, HUGH M. BOAL, a citizen of the United States, residing at Corry, in the county of Erie and State of Pennsylvania, have invented new and useful Improvements in Circuit-Breakers, of which the following is a specification.

This invention relates to improvements in circuit breakers and has particular application to a circuit breaker for opening the local sounder circuits of telegraph apparatus working on the closed circuit principle.

In carrying out the present invention, it is my purpose to provide a circuit breaker of the class described whereby the local sounder circuits of telegraph systems of the closed circuit type will be opened and held open while the line is idle, thereby preserving the life of the local batteries and enabling the use of open circuit batteries to energize the sounders.

It is also my purpose to provide a circuit opening device which will be under the control of the line relay and actuated thereby to open the controlled local circuit when the line is idle.

Furthermore, I aim to provide a circuit breaker which will embrace the desired features of simplicity, efficiency and durability, which will operate effectively under all conditions and which may be readily and conveniently installed.

With the above and other objects in view, the invention consists in the construction, combination and arrangement of parts hereinafter set forth in and falling within the scope of the claims.

In the accompanying drawing, Figure 1 is a view in elevation of a circuit breaker constructed in accordance with the present invention, the same being shown in use. Fig. 2 is a cross sectional view on the line 2-2 of Fig. 1. Fig. 3 is a similar view on the line 3-3 of Fig. 1.

Referring now to the drawing in detail, 1 designates an inverted substantially U-shaped supporting frame having a long limb 2 and a relatively short limb 3. Fastened to the inner face of the short limb 3 and depending therefrom and spaced apart are parallel contact strips 4, 5 insulated from each other by means of a block of insulating material 6 and from the adjacent face of the limb 3 by means of a strip of insulation 7. The lower extremity of the contact strip 5 is bent at right angles to itself as at 8 and

adapted to engage the adjacent portion of the contact strip 4. Fastened to the inner surface of the limb 2 adjacent to the lower end thereof is a yoke 9 having the opposite limbs thereof lying in planes parallel with the limbs of the frame 1. Threaded through alining openings in the limb 2 and the adjacent limb of the yoke is an adjustable stop screw 10, while threaded through an opening in the opposite limb of the yoke and alining with the stop screw is an adjustable back stop screw 11.

12 designates the line relay comprising the coils 13 and armature 14 under the influence of the poles of the coils of the relay and pivoted at one end as at 15 for swinging movement. In the present instance, the coils of the relay 13 are disposed in a horizontal plane and the circuit closer is supported upon a block 16 resting upon the upper surface of the coils and suitably secured thereto, while the armature 14 is disposed vertically and swings about a horizontal pivot. A coiled expansion spring 17 has one end fastened to the armature and the opposite extremity secured to an appropriate part of the frame of the relay, such spring acting to maintain the armature 14 out of engagement with the adjacent pole faces of the coils of the relay. Uprising from the upper extremity of the armature 14 and suitably fastened thereto is an armature lever 18 having the upper end thereof interposed between the confronting surfaces of the lower end of the contact strip 4 and the adjustable back stop screw 11 and equipped with a contact 19.

20 designates the local circuit including the sounder 21 and local battery 22. One terminal of the circuit 20 is connected with the contact strip 5 and the opposite end thereof secured to the armature 14 at the pivot point thereof.

In practice, when the line relay 13 is energized and deenergized, the armature 14 and lever 18 are swung back and forth in accordance with the rapidity of the current impulses in the windings of the relay and in the forward movement of the armature and armature lever under the action of the relay the contact 19 engages the lower extremity of the contact 4 thereby completing the local circuit 21 and energizing the sounder, while when the armature is relieved of the influence of the poles of the windings of the relay the spring 17 reacts

and withdraws the contact 19 out of engagement with the lower end of the contact strip 4 thereby breaking the local circuit. In the initial movement of the armature lever 18 under the action of the relay the contact 19 engages the lower end of the contact strip 4 thereby closing the sounder circuit as previously described, while in the continued movement of the lever under the action of the relay the contact strip 4 is swung out of engagement with the bent end 8 of the strip 5 thereby breaking the sounder circuit and when the line relay is energized and the line idle the armature lever 18 and lower extremity of the contact strip 4 remain against the front stop screw 10 thereby holding the local circuit 20 open and the sounder deenergized.

Suitably fastened to the short limb 3 of the supporting frame 1 and passed through an opening in the relatively long limb 2 of such frame is a threaded shank 23 upon which is threaded a thumb nut 24 which, when tightened, acts upon the shank 23 to draw the short limb 3 toward the limb 2 of the frame whereby the distance between the lower extremity of the contact strip 4 and the contact 19 on the upper end of the armature lever 18 may be varied.

30 From the foregoing description taken in connection with the accompanying drawing, the construction, mode of operation and manner of employing my invention will be readily apparent.

35 It will be seen that I have provided a circuit opener or breaker whereby the local sounder circuits of telegraph systems of the closed circuit type may be held open by the line relay when the line is idle.

40 While I have herein shown and described one preferred form of my invention by way of illustration, I wish it to be understood that I do not limit or confine myself to the precise details of construction herein 45 described and delineated, as modification and variation may be made within the scope

of the claims without departing from the spirit of the invention.

I claim:

1. A circuit breaker of the class described comprising an inverted U-shaped supporting frame having a short limb and a relatively long limb, contact strips carried by said short limb and insulated therefrom and normally in engagement with each other, a local circuit having one terminal connected with one of said strips, a line relay, a connection between the armature of said relay and the other terminal of said circuit, and a lever connected to said armature and movable therewith under the action of the coils of the relay to engage one of said contact strips to close the local circuit in the initial movement thereof and to break such local circuit in the continued movement thereof. 60

2. A circuit breaker of the class described comprising an inverted U-shaped supporting frame having a short limb and a relatively long limb, contact strips carried by said short limb and insulated therefrom and normally in engagement with each other, a local circuit having one terminal connected with one of said strips, a line relay, a connection between the armature of said relay and the other terminal of said circuit, a lever connected to said armature and movable therewith under the action of the coils of the relay to engage one of said contact strips to close the local circuit in the initial movement thereof and to break such local circuit in the continued movement thereof, and means for drawing said short limb toward said long limb whereby the space between said armature lever and the adjacent contact strip may be varied. 85

In testimony whereof I affix my signature in presence of two witnesses.

HUGH M. BOAL.
